UNITED STATES PATENT OFFICE.

ARTHUR F. THURNAU, OF CHICAGO, ILLINOIS, ASSIGNOR TO LAWRENCE AIRPLANE MODEL AND SUPPLY COMPANY, OF CHICAGO, ILLINOIS, A CORPORATION OF DELAWARE.

TOY AEROPLANE.

1,348,971.

Specification of Letters Patent. Patented Aug. 10, 1920.

Application filed October 10, 1919. Serial No. 329,849.

To all whom it may concern:

Be it known that I, ARTHUR F. THURNAU, a citizen of the United States of America, and a resident of Chicago, Illinois, have invented a certain new and useful Improvement 5 in Toy Aeroplanes, of which the following is a specification.

This invention relates to toy flying machines of the aeroplane type, and more particularly to those which are driven by a 10 propeller operated by a rubber band which is twisted one way to give it the required tension, and the untwisting of which furnishes the power necessary for propelling 15 the toy through the air.

The object of the invention is to provide a novel and improved means for securing the wings or planes to a longitudinal member and for securing the brackets for the 20 driving mechanism in place on said member, the latter being preferably a light stick of wood, and the wings or planes being preferably of aluminum or other light sheet material.

It is also an object to provide certain details and features of construction tending to increase the general efficiency and the desirability of a toy aeroplane of this particular character.

To these and other useful ends the invention consists in matters hereinafter set forth and claimed and shown in the accompanying drawings, in which—

Figure 1 is a perspective of a toy aeroplane embodying the principles of the invention.

Fig. 2 is an enlarged longitudinal section of the rear end portion of said toy.

Fig. 3 is a similar view showing the forward portion of said toy.

Fig. 4 is a transverse section on line 4—4 in Fig. 3.

Figs. 5, 6, 7 and 8 are perspectives of the various brackets and the devices by which 45 the wings or planes and the driving mechanism are mounted on the stick or longitudinal member.

As thus illustrated, the invention comprises a longitudinal member 1 which is 50 preferably a stick of wood, such as light pine or other soft or suitable wood. The wings or planes 2 are secured upon the rear portion of this longitudinal member, and the wings or planes 3, which latter constitute 55 the elevator of the toy aeroplane, are se-

cured upon the forward portion of the said member. These wings or planes are of any suitable sheet material, such as sheet aluminum, as the latter is thin and light and at the same time has sufficient stiffness to serve the 60 purpose. Fastening devices are employed to secure the said wings or planes in place, as shown, and those for the rear or larger planes or wings are located at the front and rear edges of the sheet metal, each fastening device being of the kind shown in Fig. 6, the said device comprising a flat body portion 4 which rests upon the top of the member 1, and downturned portions 5 which tightly embrace the said member, and 70 which have holes or indentations 6 punched or pressed therein to provide projections on the inner surfaces, which projections enter the wood stick or member 1 and thus hold the fastening device in place thereon. The 75 tongue 7 extends upwardly through the slot 8 in the sheet metal of the wings or planes, and is then bent downwardly upon the upper surface of the sheet metal, thereby to tightly clamp the wings or planes upon the body 80 portion 4, and in effect upon the stick or wood member. By referring to Fig. 1, it will be seen that the wings or planes 3 constituting the elevator are held in place by similar sheet metal fastening devices having 85 tongues 7, and with this arrangement the sheet aluminum or other sheet material is firmly and securely held upon the longitudinal member in such a manner that it does not tend to tear away or break away from 90 the body member 1, it being understood that the front end of the latter will impinge upon the ground when the toy descends after its flight through the air. This shock imposes a strain upon the wings, but with the sheet 95 metal fastening devices shown and described the construction is such that the wings or planes will remain firmly secured to the longitudinal member.

The propelling mechanism comprises a 100 two-bladed propeller 20 suitably secured to the rear end of a shaft 9 to which a rubber band 10 is secured, the latter having its other end secured to a hook 11 on the front end of the toy. Said hook is formed from 105 sheet metal, as shown in Fig. 8, and has a flat body portion 12 which rests upon the top of the longitudinal body member 1, and is formed with down-turned side portions 13 which tightly embrace the member 1, and 110

which have small holes or indentations 14 formed therein to provide projections which enter the wood of the member 1 to hold the hook firmly in place, all formed from a flat sheet metal blank. The shaft 9 is supported in bearings provided by the upstanding members 15 which have holes 16 for said shaft; and it will be seen that these upstanding members 15, which are spaced a suitable distance apart behind the rear edge of the wings or planes 2, are formed integral with the flat body portion 17 which rests flatwise upon the top of said longitudinal member; and, in addition, this flat portion 17 is provided with integral down-turned portions 18, like those previously described, which have holes or indentations 19 formed therein (to secure the portions 18 to the wood stick or member 1 which forms the body of the toy), as shown, all formed from a flat sheet metal blank.

Thus the wings and the propelling mechanism are all secured to the longitudinal body member 1 by means of sheet metal fastening devices, in a manner which tends to prevent breakage, but in a way which keeps the cost of manufacture comparatively low, the entire structure, with the exception of the rubber band and its shaft, and except for the body member 1 of wood, being formed of sheet metal. If the stick 10 should break, the side portions 5 and 13 and 18 of the various sheet metal fastening devices can be pried apart, or spread, thereby detaching them from the broken stick, and a new stick can then be inserted, after which the said sheet metal portions can be compressed upon the new stick to hold the parts in place.

40 It will be understood, of course, that the toy is operated by first rotating the propeller backward, thereby to twist the rubber band, and by then launching the toy forward into the air, the untwisting of the rubber band then causing the propeller to rotate forward and thereby propel the toy through the air.

What I claim as my invention is:

1. In a toy aeroplane, the combination of 50 a longitudinally disposed body member, wings or planes comprising sheet material having a slot therein, said planes extending laterally from said member, a sheet metal

fastening device formed with a flexible tongue inserted through said slot and bent 55 over upon said sheet material to clamp a portion of the material flatwise upon the top of said device, having means whereby the portion of said device underlying the sheet material is secured to said member, and propelling mechanism carried by said member.

2. A structure as specified in claim 1, said device being at the rear edge of said wings or planes, and a similar device whereby the front edge of the sheet material is also secured to said member.

3. In a toy aeroplane, a longitudinal member, wings or planes secured to said member, a sheet metal bearing comprising a flat portion seated on said member and having up-turned front and rear portions formed with holes and having down-turned side portions which are secured to the sides of said member, a shaft in said holes, a propeller on said shaft, and means extending over the planes 75 to rotate said shaft.

4. In a toy aeroplane, the combination of a longitudinal member, a device having a portion bent upward and over at its end to form a hook and having down-turned side 80 portions to tightly embrace said member, all formed from a flat sheet metal blank, a rubber band removably hitched to said hook, wings or planes secured to said member, under said rubber band, adjacent to the edge 85 of said planes, and a propeller operated by said rubber band.

5. A structure as specified in claim 1, said securing means of said fastening device comprising down-turned side portions which 90 tightly embrace said member.

6. In a toy aeroplane, the combination of a longitudinal member, and a device comprising a flat portion which rests flatwise upon said member and having integral 95 down-turned side portions which tightly embrace said member and having upper integral means for holding an instrumentality of the toy in position on said member, all formed from a flat sheet metal blank, a 100 rubber band extending over the upper surface of the toy, above said member, and a propeller operated by said rubber band.

Signed.

ARTHUR F. THURNAU.
